UNITED STATES PATENT OFFICE.

ROBERT LEE DENNISON, OF KANSAS CITY, MISSOURI.

MACHINE FOR MAKING FENCE-POSTS.

No. 853,069.

Specification of Letters Patent.

Patented May 7, 1907.

Application filed July 19, 1906. Serial No. 326,906.

To all whom it may concern:

Be it known that I, ROBERT LEE DENNISON, a citizen of the United States, and a resident of Kansas City, in the county of Jackson and State of Missouri, have invented certain new and useful Improvements in Machines for Making Fence-Posts, of which the following is a specification.

This invention is an improvement in machines for making fence posts, and relates particularly to that class of such machines illustrated in my former application for Patent No. 257,109, filed in the United States Patent Office April 24, 1905; and the invention consists in certain novel constructions and combinations of parts as will be herein-after described and claimed.

In the drawings Figure 1 is a side elevation partly in section of the machine, in the direction of the arrow No. 1 of Fig. 2. Fig. 2 is a top plan view of the machine. Fig. 3 is a detail vertical section on about line 3—3 of Fig. 2. Fig. 4 is a sectional elevation, partly broken away of the machine, drawn through one of the mold boxes and alongside the packer. Fig. 5 is a detail vertical section on about line 5—5 of Fig. 2. Fig. 6 is an end elevation of the mold box sections with the filling plates, used in boring the same, in place. Fig. 7 is a detail vertical section showing the connection between the head of the former and its reciprocating piston rod. Fig. 8 is an end view Fig. 9 an inner face view, and Fig. 10 a side view of one of the pans for use in handling the green posts. Fig. 11 is a side elevation, partly in section of a machine embodying the invention, taken in the direction of the arrow No. 11, in Fig. 2, Fig. 12 illustrates the rack stem of the packer in cross-section. Fig. 13 is a side view of a part thereof, and Fig. 14 is a detail view partly in section showing the cylinder and its piston for revolving the carrier step by step.

In the present machine are embodied many of the features of the machine illustrated in my former application for patent above referred to and it involves in addition certain improvements as will be more fully described hereinafter. Thus in the present invention, I employ in connection with the main frame, substantially like that shown in my former application for patent, a carrier A to which the mold boxes B are secured, and which carrier revolves around a central main shaft a, which is hollow, and forms a

pump cylinder in connection with a plunger a³ connected with the former T and reciprocated therewith in the operation of the invention.

The pump cylinder is connected by a pipe a' having a check valve a², with a suitable source of supply of oil, which is drawn into the cylinder a in the operation of the machine. The plunger a³ is provided with a check valve a⁷ and is connected by a pipe connection a⁶ with a channel formed in the piston rod V⁷ with which the former T is connected for reciprocation, and the former T being made hollow as shown at a⁴, and having numerous perforations a¹⁴, through which the oil supplied may be discharged to the post in the operation of molding the same. This former T is reciprocated by means substantially the same as those described in my former application for patent, and including the cylinder V, see Fig. 11, and the former T has its head T' swiveled on the lower end of the piston rod V⁷ so it may be turned by the means provided for such purpose, in the operation of the invention, without turning the piston rod V⁷, by which the former T is reciprocated in the operation of the machine. Thus, as the former reciprocates, the plunger a³, operating in the pump cylinder a draws the oil into the said cylinder a and forces it to the follower T, from whence it discharges to the concrete within the mold box, as will be understood from Fig. 11 of the drawings.

In effecting the joint between the piston rod V⁷ and the head of the plunger T, the lower end of the rod V⁷ is provided with a flange V⁸ which fits in a contracted bore T⁶ within the head of the former T and bears upon rollers T³, rollers T⁴ operating above the flange V⁸ and a shoulder V¹⁸ being provided above the rollers T⁴ to receive a bearing plate V¹⁹, above which gaskets V²⁰ are arranged to be pressed upon by the gland T¹² so pressure may be exerted upon the gaskets to preserve an oil tight joint without producing undue pressure upon the antifriction rollers.

In forming the mold box with sections G and G², it is preferred to bore the same in such manner that the mold box sections are segments of the circles on which the bores of the mold box are struck. Thus, referring to Fig. 6, in boring the sections G and G² of the mold box, I prefer to place iron strips g between the flanged edges of the sections and then turn the interior out with a boring bar

perfectly round, and after such boring, the strips g are removed and it will be noticed then that the bore of the mold boxes will be slightly out of a true circle, the effect of which is to prevent the material being formed into a post from turning within the mold box when the pressure of the former T is operating within the material forming the post. This feature of holding the material from turning in connection with the lubricating plunger makes it possible to produce a practically perfect post, which cannot be effected otherwise as the plunger when lubricated will stick to the material in the mold box and cause it to turn within the box, when the latter is round, which has the effect of tearing the post and injuring its inner surface, and seriously impairs the solidity and efficiency of the post.

In Figs. 8, 9 and 10, I illustrate a pan for use in removing the green posts from the mold boxes. This pan G^3 conforms generally to the shape of the post, is open at one side so it can be readily slipped onto one side of the post within the mold box, has a bottom plate G^7 to slip under the green post, and is provided on its outer side with handles G^4 so it can be conveniently manipulated in removing the green post from the mold box and placing it in position to dry.

I also employ in the present machine, a packer O for feeding the material into and packing it within the mold boxes preparatory to the operation of the former T . This packer O is in the form of a spiral and is preferably of such length as to extend the entire length of the mold box to insure the perfect packing of the material in the mold. At its upper end the packer O is provided with a disk O' and above said disk with a rack shaft O^2 having circular rack teeth extending around it and provided along the said rack teeth with a key way O^3 by which the key in the pinion O^{12} operates to turn the rack shaft O^2 , and at the same time permits the movement longitudinally of the said rack shaft through the pinion O^{12} , as said shaft ascends and descends in the operation of the machine. The disk O' serves as an abutment for operating various levers, provided for different purposes as will be hereinafter more fully described. The pinion O^{12} for revolving the packer O is turned by a pinion O^{13} on the shaft of a motor P , which motor P is provided with a controlling lever P^{11} having a hanger P^{12} whose lower end extends through the platform Q , and projects in position to be operated by the disk O' when the latter approaches its uppermost position, as will be understood from Fig. 4 of the drawings.

The rack shaft O^2 drops by gravity and is raised by means of the pinion O^3 meshing with the rack teeth of the said rack shaft O^2 and secured upon a shaft O^5 , which shaft is

journaled in brackets on the platform Q , and has keyed to it a brake wheel O^6 , and friction disk O^7 and supports adjacent to the latter the gear O^4 loose on the shaft O^5 and geared with the pinion on the shaft of a motor O^{15} , which motor O^{15} may be regulated by the controller O^{36} , as shown in Fig. 2 of the drawings.

The brake wheel O^6 receives the band brake O^{11} connected with the lever O^{21} having a hanger O^{22} arranged to be operated upon by the disk O' as the latter reaches its uppermost position. By this means it will be noticed that the disk O' as it approaches its uppermost position operates the motor P , through the hanger P^2 , and also operates to set the brake O^{11} through the hanger O^{22} . The motor O^{15} has a continuous operation which may be regulated by the controller O^{36} and gives a continuous motion to the gear O^4 , which gear is loose upon the shaft O^5 so that the shaft O^5 is turned by the gear O^4 when means are provided for clutching the gear O^4 to the shaft O^5 . This is the purpose of the friction disk O^7 which is pressed by the spring O^8 toward the gear O^4 and is operated by the yoke O^{16} away from the said gear, the said yoke O^{16} being keyed on the shaft O^{14} and said shaft being operated in a manner which will presently be described. This shaft O^{14} is provided with a depending crank arm O^{17} connected with the forwardly projecting link O^{18} adapted to release the latch O^{19} of the depending bar O^{22} whereby to release the brake O^{11} after the disk O' has descended from the position shown in Fig. 3 of the drawings. The shaft O^{14} is also provided with a laterally projecting crank arm O^{23} to which is connected the hanger rod O^{26} , which extends down to the revolving carrier and is provided at its lower end with a pivoted foot-piece V^2 having a roller V^4 which is operated upon by tripping projections V^5 on the revolving portion of the carrier as best shown in Fig. 4 of the drawings. The bar O^{20} is guided at its lower end in a bracket I mounted on the framing of the machine, and this bracket also forms a pivot for a bell crank lever P^2 , one arm of which extends into the path of the disk O' for engagement thereby as it is being lowered, and the other arm of said bell crank lever P^2 is connected by the links P' with the pivoted foot-piece V^2 so it may operate the said foot-piece in opposition to the spring P^3 and pull the said foot-piece V^2 from the position shown in Fig. 4 to the right where it will drop from the cam projection V^5 and permit the rod O^{26} to lower, thus releasing the friction disk O^7 and permitting the same to be forced by the action of its spring O^8 as well as by the gravity of rod O^{26} into frictional engagement with the gear O^4 , so the friction disk O^7 and the shaft O^5 will be operated from the disk O^7 in order to lift the packer by the gearing of the

pinion O^3 with the rack O^2 , as before described, it being understood that the pinion O^3 is sufficiently wide to prevent any interference with the mesh of the parts by the passing of the key-way in the rack O^2 , as the said rack is revolved in the operation of the machine.

On the opposite side of the pivoted foot-piece V^2 from the spring P^3 , I provide a cam loop or projection V^3 . In case the material should fall into the mold box to such an extent as to prevent the packer O from dropping down low enough to bring the disk O' into operative contact with the lever P^2 so as to release the arm V^2 from its position on the lug or projection V^3 , the motor would not be set to lift any part of the weight of the packer, and to overcome this objection I provide on the cross-head t of the former T a roller V^6 , which on the downward movement of the former T will engage with the cam loop or projection V^3 and force the arm V^2 off the cam projection V^3 in the same manner as if such operation had been effected by the engagement of the disk O' with the lever P^2 , thereby insuring perfect uniformity of the entire movements of the machine.

When from any reason a variation in the density of the packed material becomes necessary or desirable, it may be controlled by the motor O^{15} by the moving of the lever O^{38} from point to point to increase or diminish the power of the motor, as is well known by those skilled in such art. It is to be understood that the motor will by its connections with the gear wheel O^4 on the shaft O^5 and the pinion O^3 on said shaft, lift any part of the weight of the packer O , and as the weight of the packer is lifted in whole or in part by the motor, it will require less density of the material in the mold box to force the material out of the mold box so that it is possible to vary at the will of the operator, the amount of material formed into a post.

In the operation of the improved machine when the carrier A has revolved to bring the mold box B directly under the packer O , one of the legs or projections V^5 on the carrier will be brought to a position beneath the pivoted foot-piece of the rod O^2 and the said rod by its connections with the shaft for operating the friction disk will move said friction disk out of engagement with the gear wheel O^4 and the devices O^{17} and O^{18} operated from the shaft O^{14} will compress the latch O^{19} , permitting the bell crank of the brake band to drop, thus releasing the shaft O^5 so that the packer O may drop to the bottom of the mold box B . As soon as the disk O' has operated the lever P^2 , the foot-piece of the rod O^2 will be lowered and the motor P will start to revolve the packer O through the pinions O^{12} and O^{13} in such manner as to pack the material to be molded into the mold box. As the material in the mold box is

packed to the desired density, the packer O through the action of its spiral blades will climb upwardly within and be forced out of the mold box when the disk O' will by contact with the arm O^{22} set the band brake, 70 and the latch O^{19} engaging the frame Q will hold the packer suspended until the carrier A moves another empty mold box under the packer when the contact will again be made with the projection V^3 and the foot-piece on 75 the rod O^2 , when the operation will be repeated as before.

The means for revolving the carrier may be substantially the same as shown in my former application, before referred to. I have, however, illustrated in Fig. 14 a construction of cylinder S with an improved valve S' , which may be preferred in some instances.

Having thus described my invention, what I claim as new and desire to secure by Letters Patent is—

1. In a machine for molding plastic articles, the combination of a revoluble carrier having mold boxes, a hollow shaft centrally 90 of said carrier and forming a pump cylinder, a supply pipe, a check valve controlling the same, a hollow plunger piston and check valve, a hollow former having discharge openings, and a connection between the hollow former and the hollow plunger, substantially as set forth.

2. In a machine for molding plastic articles, the combination of a mold, a hollow former reciprocating and revolving in said mold, and having oil discharge openings, and means for supplying oil to said former.

3. The combination in a machine for molding plastic articles, of a mold box, a former revolving and reciprocating therein, a pump having a plunger reciprocating with the former, and means for conveying the pump material to the former.

4. The combination in a machine for molding plastic articles, of a central hollow shaft forming a pump cylinder, a carrier revolving about the said shaft and having mold boxes, a hollow plunger reciprocating in the pump cylinder, a former, a tube connecting the former with the plunger, and means for turning and reciprocating the former.

5. The combination in a machine for molding plastic articles, of a piston rod having an oil conduit, a hollow former having oil discharge openings and swiveled in the piston rod and communicating with the oil conduit therein, a stuffing-box controlling the joint between the former and the piston rod, a pump cylinder, a hollow plunger operating in said cylinder, and a supply pipe connecting said hollow plunger with the piston rod whereby oil may be conveyed to the conduit of the piston rod and the plunger will be reciprocated by the movements of the piston rod, substantially as set forth.

6. In a machine for molding plastic articles, the combination of a piston rod having an oil conduit and a supply pipe leading thereto, a hollow former swiveled on the piston rod and having oil discharge openings, the said former communicating with the oil conduit in the piston rod, and a stuffing-box controlling the joint between the former and the piston rod.
- 10 7. The combination in a machine substantially as described of a revolving carrier having mold boxes arranged to be successively presented to a packer, a packer arranged to reciprocate and revolve in said mold boxes, and provided with an upwardly projecting rack shaft having a key-way and at the base of said rack shaft with a tripping disk, a motor and gearing connecting the same with the rack shaft, including a pinion keyed on 15 the said shaft, and means controlling said motor including devices depending in position for engagement by the disk at the base of the rack shaft, substantially as set forth.
8. The combination of a revolving carrier 25 having mold boxes and provided with cam projections or lugs, a packer adapted to operate in the mold boxes and having an upwardly projecting rack shaft, a motor mechanism for turning the said shaft, a shaft having a pinion meshing with the rack shaft and also provided with a loose gear, a motor driving said loose gear, clutch mechanism between said loose gear and its supporting shaft, a depending rod arranged for operation 30 by the lugs or cam projections on the carrier, intermediate mechanism between said depending rod and the clutch mechanism whereby the said rod may operate the clutch mechanism, and intermediate devices 35 between the packer and the said depending rod whereby the same may be freed from engagement with the cam lugs or projections of the carrier, substantially as set forth.
- 40 9. The combination with a revolving carrier, its mold boxes and cam lugs or projections, of a packer arranged to revolve and reciprocate in the mold boxes and provided with an upwardly projecting rack shaft, means for turning the shaft, a pinion meshing with the rack shaft whereby to lift the packer, a motor mechanism, intermediate devices between the motor mechanism and said pinion and including a clutch mechanism, and means whereby the clutch mechanism 45 may be operated from the cam lugs or projections of the carrier, substantially as set forth.
10. In a machine for molding plastic articles, the combination with a revolving carrier having mold boxes, of a packer arranged to descend by gravity into said mold boxes, devices for lifting said packer, and means controlling said lifting devices from the carrier, substantially as set forth.
11. The combination with a revolving carrier having mold boxes and also provided with cam lugs or projections, of a packer adapted to reciprocate and rotate within the said boxes, means for turning the said shaft, 70 devices for raising the shaft and including a motor mechanism and a clutch, a depending rod, intermediate devices between the said rod and the clutch mechanism, the said rod being provided at its lower end with a pivoted foot-piece arranged to operate upon the cam lugs or projections of the carrier, and means for operating said foot-piece from the packer, substantially as set forth.
12. The combination with a revolving carrier having cam lugs or projections and a packer having a disk, and mechanism for lifting the packer, of a depending rod arranged to operate upon the mechanism for lifting the packer, and provided at its lower end 85 with a pivoted foot-piece operating upon the cam lugs or projections of the carrier, a bell crank lever connected with the foot-piece and arranged for operation by the disk of the packer, and a spring for readjusting 90 the foot-piece, substantially as set forth.
13. The combination of the carrier having the mold boxes and the cam lugs or projections, a packer, devices for lifting the packer, means for controlling the lifting devices including a depending rod having a pivoted foot-piece arranged for engagement by the cam lugs or projections, devices for operating said pivoted foot-piece from the packer, a reciprocating former, and devices in connection with said former for operating upon the pivoted foot-piece whereby to actuate the same under unusual circumstances, substantially as set forth.
14. The combination with a revolving carrier having mold boxes, of a packer adapted to reciprocate and revolve within the mold boxes and provided with an upwardly projecting rack shaft, means for rotating the rack shaft and packer, a shaft having fixed thereon a pinion meshing with the rack shaft, a gear loose on said shaft, means for driving said gear, a brake device having a disk fixed on the shaft, means for setting said brake from the packer, a clutch mechanism 110 whereby to connect the gear with the shaft, and means for operating the clutch device from the carrier, substantially as set forth.
15. The combination of the carrier having mold boxes and cam lugs or projections, a reciprocating packer having a rack shaft, means for revolving the packer, a shaft having a tight pinion meshing with the rack shaft and also provided with a loose gear, and with a brake disk and a friction disk keyed on the 115 shaft, a spring tending to set the friction disk into engagement with the loose gear, motor mechanism geared with the loose gear, a brake device operating on the brake disk and arranged to be set from the packer, means for 120
- 65 125
- 130

- releasing the friction disk from the gear and including a depending rod arranged for operation by the cam lugs or projections of the carrier, and means for releasing the brake when the friction disk is freed from engagement with the loose gear, substantially as set forth. 5
16. The combination of a revolving gear having mold boxes, a packer reciprocating in said mold boxes and having an upwardly projecting rack, a shaft having a tight pinion meshing with said rack, a driven gear loose on said shaft, brake mechanism operating upon the shaft and having a depending rod arranged to be tripped from the packer and provided with a latch for holding the brake set, a friction disk keyed on the shaft and arranged to engage with the driven gear whereby to key the latter to the shaft, means for operating said disk and including a depending rod arranged for operation from the carrier, and a device connected with the disk operating means for releasing the latch of the brake mechanism, substantially as set forth. 10
17. The combination with a revolving carrier and its mold boxes, of a packer for operating in said mold boxes and having a rack shaft, a shaft having a tight pinion meshing with said rack shaft, a driven gear loose on said shaft, a brake disk keyed on the shaft, a friction disk keyed on the shaft and moving into and out of engagement with the driven gear, a brake band, means operating upon the brake band for setting the brake and including a depending rod for operation from the packer and a latch for holding the brake set, a shaft approximately at right-angles to the first said shaft and provided with a yoke for operating the friction disk, with a braking crank having means for releasing the latch of the brake mechanism, and with a second crank, and a depending rod connected with said second crank and provided at its lower end with means for operation from the revolving carrier, substantially as set forth. 15
18. The combination with a revolving carrier having mold boxes and cam lugs or projections, of a packer having a downwardly projecting rack shaft and a disk at the base thereof, means operating upon the rack shaft to revolve the packer, a pinion meshing with the rack shaft for driving the packer, a clutch mechanism for detaching the pinion from its drive mechanism, means operated from the packer when in its lowermost position for connecting the pinion with its drive mechanism, and means operating from the carrier for connecting the pinion with its drive mechanism, substantially as set forth. 20
19. The combination in a machine for molding plastic articles with a revolving carrier having mold boxes and cam lugs or projections, of a reciprocating packer, mechanism for raising the said packer, the latter being adapted to descend by gravity, means for driving said raising mechanism, a depending rod, intermediate devices whereby the said rod may connect the driving means with the raising mechanism, means operated from the carrier for actuating the rod to connect the driving means with the raising mechanism, the said rod being arranged for operation by the cam lugs or projections of the carrier to release the driving means from the raising mechanism, substantially as set forth. 25
20. The combination with a revolving carrier, its mold boxes and its lugs or projections, of a reciprocating packer operating in the mold boxes and provided with a rack shaft and at the base thereof with a projecting disk, gearing for revolving the packer, a pinion meshing with the rack shaft for raising the packer, a brake mechanism for retarding the movement of the pinion, a drive gear for turning the pinion, a clutch for keying the drive gear in connection with the pinion, means for operating the brake by the disk of the packer, a depending rod arranged to operate the friction disk and provided at its lower end with a pivoted foot-piece for engagement with the cam lugs or projections of the carrier, and a bell crank lever having one arm connected with said pivoted foot-piece and its other arm arranged for operation by the disk of the packer, substantially as set forth. 30
